2 Claims. (Cl. 139—170.3)

This invention relates to looms, and more particularly to weft restraining devices for multi-shuttle looms, and especially those equipped with change boxes, and particularly drop boxes or the like.

In multi-shuttle looms, e.g., of the type wherein the shuttle change is effected by means of a drop box, the compartment accommodating the shuttle with the weft color desired, is brought into alignment with the path of the slay—the proper selection being controlled by a pattern card. Change mechanisms of this kind are known to suffer from the grave defect that frequently, during the change operation, the several weft threads become entangled with one another, often with the result that on picking not only the weft thread derived from the shuttle aligned with the path of the slay, but also threads from adjacent shuttles are introduced into the fabric being woven. These unwanted threads must then be removed again individually, which is a delicate and hence hard and time consuming task.

It is the primary object of the present invention to eliminate this problem, and to effectively prevent the entanglement of weft threads deriving from different shuttles, particularly during a shuttle change operation.

It is another object of the invention to provide means for preventing weft entanglement which are simple in construction and operation and therefore, vastly improve the shuttle change procedure without adding materially to the cost of manufacture or operation of the loom.

A further object of the invention is the provision of weft entanglement preventive devices which are susceptible of incorporation in existing looms.

Other objects, and the manner in which the same are obtained, will become apparent as this specification proceeds.

Viewed in its broader aspects, the invention contemplates providing a multi-shuttle change box, and preferably a drop box with superposed compartments, on the side facing the slay, with a pneumatic suction system for restraining or securing the individual weft threads. In accordance with the basic principles of the invention, the weft threads emerging from the several shuttle compartments are pneumatically placed under tension, in the region between the shuttle compartment and the fabric being woven, whereby any entanglement of the several weft threads in this region is effectively eliminated.

Regarded somewhat more specifically, the invention encompasses orifices correlated with the individual shuttle compartments of a drop box, for example, and suction conduits deriving from a suction main, leading to individual orifices.

In the drawing accompanying this specification and forming part thereof, several embodiments of the invention are illustrated diagrammatically by way of example.

In the drawing:

FIG. 1 illustrates a preferred embodiment of the invention in a diagrammatic side view, seen with a suction system, and the view taken from the opposite side of the individual shuttle compartments of the drop box, and

FIG. 2 is a plan view, partly in horizontal section, of a modification of a detail of FIG. 1, drawn to a larger scale.

FIG. 1 shows a preferred embodiment of the inven-

2

tion which includes a drop box 1 comprising four compartments 2 each containing a shuttle (shown in dashes) arranged on one side of the slay or lay.

The side wall of the drop box facing the operator comprises, in the region where the compartments 2 open toward the slay, suction orifices 11 each of which is connected with an individual suction tube 12 (shown in dashes in FIG. 1). All suction tubes 12 open into a suction main 13 which is connected to a suction pipe leading to a suction pump.

The suction orifices 11 have an oblong configuration and extend horizontally. The top shuttle compartment 2 is provided with a single suction orifice 11 which is disposed in the bottom half of the compartment. Similarly, the bottom compartment is equipped with only one suction orifice, which, however, is situated in the upper half of the vertical wall of the compartment. The remaining compartments, however, are each provided with two suction orifices 11 one of which is located in the upper half of the compartment wall, while the other is disposed in the lower half of said wall.

As shown in FIG. 2, the suction pipes 12 shown in FIG. 1, which connect the suction orifices 11 provided in the side wall of the drop box, with the suction main 13, can be replaced by suction channels 14 which are arranged in the wall of the drop box.

The effect that the pneumatic suction device of FIGS. 1 and 2 has on the weft threads 9, is apparent from the disposition of these threads in FIGS. 1 and 2. Weft threads 9 deriving from shuttle compartments which are situated just above the race board 5, are exposed to suction emanating from the bottom orifice in said compartment, while weft threads 9 which derive from shuttle compartments disposed just below the race board 5, are exposed in each instance to the orifice in the top part of each compartment. The weft thread 9 deriving from the shuttle which is disposed just in the plane of the race board 5 (i.e., the second shuttle from the top in FIG. 3), can be drawn in by suction emanating from the orifice in the upper half of the compartment, as well as by the orifice in the lower half of the compartment. For this reason, the walls of the top and bottom compartments, respectively, may be provided with a single orifice only.

Manifestly, the suction system of the invention, and particularly the several embodiments shown and described herein, is susceptible of use in connection with drop boxes comprising a different number of compartments, such as six instead of four compartments, for example.

For picking purposes, the shuttles are conveyed into the plane of the race board of the slay, the race board serving as the gliding surface. The stroke of the drop box is controlled to convey any one of the shuttles into the plane of the race board.

The invention may be further elaborated by a number of refinements. For example, the compartment walls provided with orifices according to FIGS. 1 and 2, may have groove-like recesses leading toward the orifices, for preventing the shuttle when it leaves the compartment, from forcing the weft thread against the edges around the orifices, thus damaging or cutting the thread. The inner edges of the suction orifices may be rounded, for the same purpose.

I wish it to be understood that I do not desire to be limited to the details of construction, design and operation illustrated and described, as numerous modifications embraced by the appended claims and involving no departure from the spirit of the invention nor any sacrifice of the advantages thereof, are likely to occur to persons skilled in the art.

I claim:

1. In a multi-shuttle loom comprising a lay including a race plate and a drop box including a plurality of com-

partments arranged on the side of said lay, shuttles being disposed in said compartments and weft threads deriving from said shuttles extending toward said lay, and pneumatic suction means for attracting and restraining individual weft threads to prevent the mutual entanglement thereof in the region between said drop box and the adjacent selvage of the cloth, said suction means comprising suction orifices adjacent the mouths of the individual compartments of the drop box and at least one suction conduit leading to said suction orifices, said drop box comprising at least four shuttle compartments vertically superposed on one another, one orifice being provided in the lower half of the top compartment, one orifice being provided in the upper half of the bottom compartment, and two orifices being provided in the remaining compartments, one of said two orifices being disposed in the upper half of the compartment while the other is disposed in the lower half of said compartment.

2. In a multi-shuttle loom comprising a lay including a race plate and a drop box including a plurality of compartments arranged on the side of said lay, shuttles being disposed in said compartments and weft threads deriving from said shuttles extending toward said lay, and pneumatic suction means for attracting and restraining individual weft threads to prevent the mutual entanglement thereof in the region between said drop box and the adjacent selvage of the cloth, said suction means comprising

5
10

suction orifices adjacent the mouths of the individual compartments of the drop box and at least one suction conduit leading to said suction orifices, said drop box comprising at least four shuttle compartments vertically superposed on one another and said compartments having side walls, one orifice being provided in the side wall of the lower half of the top compartment, one orifice being provided in the side wall of the upper half of the bottom compartment, and two orifices being provided in the side walls of the remaining compartments, one of said two orifices being disposed in the upper half of the compartment while the other is disposed in the lower half of said compartment.
